SNOWMOBILE HOOD

Kurt B. Boehm, Lake Bluff, Ill., assignor to Textron Inc., Providence, R.I.

Filed Nov. 19, 1970, Ser. No. 26,075

Term of patent 14 years

Int. Cl. D12—16

U.S. Cl. D14—24

FIG. 1

FIG. 3

FIG. 1 is a view in perspective as seen from the front and one side of a snowmobile hood showing my new design;

FIG. 2 is a view in perspective as seen from the front end and the side opposite that shown in FIG. 1; and

FIG. 3 is a view in top plan.

The rear and bottom not shown are substantially open.

I claim:

The ornamental design for a snowmobile hood, as shown and described.
